(57) **CLAIM**

The ornamental design for a wheeled cart, as shown and described.

DESCRIPTION

FIG. 1 is a top, front perspective view of a wheeled cart showing my new design, the broken lines are for illustrative purposes only and form no part of the claimed design;

FIG. 2 is a top plan view thereof;

FIG. 3 is a front elevational view thereof;

FIG. 4 is a right side elevational view thereof, the left side being a mirror image;

FIG. 5 is a rear elevational view thereof; and,

FIG. 6 is a bottom view thereof.
